FOOT REST

Henry Jordan, Jr., Muskegon, Mich.

Application July 23, 1934, Serial No. 736,581

12 Claims. (CL 15—265)

My invention relates to foot rests used in connection with seats in shoe shining parlors, and it primarily has for its object to provide an improved foot rest of the character stated which 5 may be swung laterally and held in a number of different positions; i. e., either straight out in front or at right angles thereto at either side so that when swung aside a clear space between a pair of rests will be left for the customer to 10 step up to the seat or get down therefrom.

Further, the invention has for an object to provide a rest having a relatively large bearing on its support and having the bearing sleeves so related and designed that the rest bracket and 15 the bearing sleeves cast integrally.

Further, it is an object to provide a swinging foot rest in which provision is made, if desired, to lubricate the bearing in a manner that will require the application of a lubricant only at 20 long intervals.

Further, it is an object to provide a foot rest with a spring catch so designed as to hold the bracket in any of its selected positions and so designed that it will tend to bring the rest into 25 one of a plurality of selected positions as the rest is moved to approximately the position desired.

Other objects will in part be obvious and in part be pointed out hereinafter.

To the attainment of the aforesaid objects and ends, the invention still further resides in the novel details of construction, combination and arrangement of parts, all of which will be first fully described in the following detailed 30 description and then be particularly pointed out in the appended claims, reference being had to the accompanying drawing, in which:—

Figure 1 is a perspective view of a shoe-shiner's settee employing my invention.

Figure 2 is a side elevation thereof.

Figure 3 is an enlarged plan view of a foot rest with the bracket swung to one side.

Figure 4 is a front elevation thereof.

Figure 5 is a detailed vertical section on the line 5—5 of Figure 2.

Figure 6 is a detailed cross section on the line 6—6 of Figure 5.

Figure 7 is a detail view showing how the parts 44—9 and 13—14 may be made integral if desired.

In the drawing, in which like numerals of reference indicate like parts in all the figures, 1 represents the base which is provided with a step 55 portion 2 and on which is mounted the riser 3,

the latter carrying the seats 4. All of the foregoing parts may be of the usual construction.

5 represents a cylindrical casting having ears 6 by means of which it may be secured to the riser 3 with screws 7 or other suitable fastening device. The ends of the cylindrical casting 5 are internally threaded as at 8. The upper end receives an upper bearing sleeve 9 which is threaded at 10 into the casting 5 while the lower end receives a lower bearing sleeve 11 threaded at 10 12 to screw into the lower end of the casting 5. The lower bearing sleeve 11 has a shoulder 13 to serve as a thrust bearing. In order to secure the upper and lower bearing sleeves against becoming unscrewed after the parts are assembled 15 the ends of the sleeves are engaged by caps 14 held in place by a bolt and nut device 16—17. The head of the bolt and the corresponding face of the nut are preferably conform and the caps 14 have conform seats 15 to receive the same. 20

If desired, the upper and lower bearing sleeves 9 and 11 may be respectively provided with small oil holes 19 in their walls and the space within the sleeves 9—5—11 between the caps 14 may be used to hold a cylindrical wick 18 of felt or other 25 suitable material which may be saturated with lubricating oil for the purpose of lubricating the bearing surfaces of the upper and lower sleeves.

The shoe rest bracket 20 has a foot portion 23 and it is also provided with upper and lower bearing sleeves 21 and 22 to fit on the upper and lower bearing sleeves 9 and 11 respectively. The upper bearing sleeve 9 is provided with V-shaped notches 24 preferably set ninety degrees apart. These notches cooperate with the latch pin 25 in a 30 hole 26 in the upper sleeve 21, the pin being pressed inwardly by means of a latch spring 27 secured to the upper sleeve 21 between the side flanges 28 of the bracket proper 20.

In assembling the parts the upper bearing 40 sleeve 9 is threaded into place through the upper bearing sleeve 21 and the lower bearing sleeve 11 is threaded up through the sleeve 22 into the casting 5 until there is a close working fit between the parts, after which the bolt 16 with caps 14 45 is placed in position and then nut 17 is screwed tightly home.

As the notches 24 are located ninety degrees apart and one of the notches is directly in front it is obvious that by moving the bracket 20 to 50 right or left it may be folded against the riser 3 in such direction as may be required to provide the desired passage way to the chair. (See Figure 1). Should the operator not swing the bracket entirely into the desired position, but 55

almost there, the V-shape of the notches in co-operation with the spring-pressed latch will tend to complete the movement so as always to keep the bracket in one or the other of the positions 5 provided for.

From the foregoing description, taken in connection with the accompanying drawing, it is thought that the complete construction, operation and advantages of my invention will be clear 10 to those skilled in the art.

What I claim is:

1. In a foot rest, a cylindrical body having its ends threaded and having ears, means to secure 15 said ears to a fixed support, an upper and a lower bearing sleeve threaded into said cylindrical body, a bracket having an upper and a lower bearing sleeve to straddle said cylindrical body and fit on the first mentioned upper and lower bearing sleeves, and a foot member carried by said bracket. 20 2. In a foot rest, a cylindrical body having its ends threaded and having ears, means to secure 25 said ears to a fixed support, an upper and a lower bearing sleeve threaded into said cylindrical body, a bracket having an upper and a lower bearing sleeve to straddle said cylindrical body and fit 30 on the first mentioned upper and lower bearing sleeves, a foot member carried by said bracket, and end caps engaging the first mentioned upper and lower bearing sleeves and a bolt with nut 35 passed through said caps, said sleeves and said cylindrical body, to close the interior thereof and secure the first mentioned upper and lower sleeves against separating. 40

3. In a foot rest, a cylindrical body having its 35 ends threaded and having ears, means to secure said ears to a fixed support, an upper and a lower bearing sleeve threaded into said cylindrical body, a bracket having an upper and a lower bearing sleeve to straddle said cylindrical body and fit 40 on the first mentioned upper and lower bearing sleeves, and a foot member carried by said bracket, the cylindrical body and the first mentioned upper and lower sleeves being hollow, the first mentioned upper and lower sleeves having lubricating 45 apertures in the walls thereof and means to deliver lubricant to said apertures. 50

4. In a foot rest, a cylindrical body having its ends threaded and having ears, means to secure 55 said ears to a fixed support, an upper and a lower bearing sleeve threaded into said cylindrical body, a bracket having an upper and a lower bearing sleeve to straddle said cylindrical body and fit 60 on the first mentioned upper and lower bearing sleeves, a foot member carried by said bracket, and end caps engaging the first mentioned upper and lower bearing sleeves and a bolt with nut 65 passed through said caps, said sleeves and said cylindrical body, to close the interior thereof and secure the first mentioned upper and lower sleeves against separating, the cylindrical body and the first mentioned upper and lower sleeves being hollow, the first mentioned upper and lower sleeves having lubricating apertures in the walls thereof and means 70 to deliver lubricant to said apertures. 75

5. In a foot rest, a cylindrical body having its ends threaded and having ears, means to secure 80 said ears to a fixed support, an upper and a lower bearing sleeve threaded into said cylindrical body, a bracket having an upper and a lower bearing sleeve to straddle said cylindrical body and fit 85 on the first mentioned upper and lower bearing sleeves, and a foot member carried by said bracket, the first mentioned upper bearing sleeve having a set of latch-pin 90 recesses spaced apart in a plane transverse of the sleeve, the second mentioned upper bearing sleeve having a pin hole, a pin in said pin hole and a spring continuously tending to advance said pin into one or another of said recesses. 95

ceiving recesses spaced apart in a plane transverse of the sleeve, the second mentioned upper bearing sleeve having a pin hole, a pin in said pin hole and a spring continuously tending to advance said pin into one or another of said recesses. 5

6. In a foot rest, a cylindrical body having its ends threaded and having ears, means to secure 10 said ears to a fixed support, an upper and a lower bearing sleeve threaded into said cylindrical body, a bracket having an upper and a lower bearing sleeve to straddle said cylindrical body and fit 15 on the first mentioned upper and lower bearing sleeves, a foot member carried by said bracket, and end caps engaging the first mentioned upper and lower bearing sleeves and a bolt with nut passed through said caps, said sleeves and said cylindrical body, to close the interior thereof and secure the first mentioned upper and lower sleeves against separating, the first mentioned upper bearing sleeve having a set of latch-pin receiving recesses spaced apart in a plane transverse of the sleeve, the second mentioned upper bearing sleeve having a pin hole, a pin in said pin hole and a spring continuously tending to advance said pin into one or another of said recesses. 20 25

7. In a foot rest, a cylindrical body having its ends threaded and having ears, means to secure 30 said ears to a fixed support, an upper and a lower bearing sleeve threaded into said cylindrical body, a bracket having an upper and a lower bearing sleeve to straddle said cylindrical body and fit 35 on the first mentioned upper and lower bearing sleeves, and a foot member carried by said bracket, the cylindrical body and the first mentioned upper and lower sleeves being hollow, the first mentioned upper and lower sleeves having lubricating apertures in the walls thereof and means to deliver lubricant to said apertures, the first mentioned upper bearing sleeve having a set 40 of latch-pin receiving recesses spaced apart in a plane transverse of the sleeve, the second mentioned upper bearing sleeve having a pin hole, a pin in said pin hole and a spring continuously 45 tending to advance said pin into one or another of said recesses. 50

8. In a foot rest, a cylindrical body having its ends threaded and having ears, means to secure 55 said ears to a fixed support, an upper and a lower bearing sleeve threaded into said cylindrical body, a bracket having an upper and a lower bearing sleeve to straddle said cylindrical body and fit 60 on the first mentioned upper and lower bearing sleeves, a foot member carried by said bracket, and end caps engaging the first mentioned upper and lower bearing sleeves and a bolt with nut 65 passed through said caps, said sleeves and said cylindrical body, to close the interior thereof and secure the first mentioned upper and lower sleeves against separating, the cylindrical body and the first mentioned upper and lower sleeves being hollow, the first mentioned upper and lower sleeves having lubricating 70 apertures in the walls thereof and means to deliver lubricant to said apertures, the first mentioned upper bearing sleeve having a set of latch-pin receiving recesses spaced apart in a plane transverse of the sleeve, the second mentioned upper bearing sleeve having a pin hole, a pin in said pin hole and a spring continuously tending to advance said pin into one or another of said recesses. 75

9. In a foot rest, a cylindrical body having its ends threaded and having ears, means to secure 80

said ears to a fixed support, an upper and a lower bearing sleeve threaded into said cylindrical body, the lower sleeve having a thrust bearing part, a bracket having an upper and lower bearing sleeve 5 to straddle said cylindrical body and fit on the first mentioned upper and lower bearing sleeves, and a foot member carried by said bracket.

10. In a foot rest, a cylindrical body having its ends threaded and having ears, means to secure 10 said ears to a fixed support, an upper and a lower bearing sleeve threaded into said cylindrical body, the lower sleeve having a thrust bearing part, a bracket having an upper and lower bearing sleeve to straddle said cylindrical body 15 and fit on the first mentioned upper and lower bearing sleeves, a foot member carried by said bracket, caps engaging said first mentioned lower sleeve and said upper sleeves and a bolt passing through apertures in said caps and through said 20 cylindrical body and said sleeves and a nut cooperating with said bolt to hold the parts together.

11. In a foot rest, an elongated body, means to 25 secure said body to a fixed support, an upper and a lower bearing sleeve held on said body, the

lower sleeve having a thrust bearing part, a bracket having an upper and a lower bearing sleeve to straddle said body and to fit on said first mentioned upper and lower bearing sleeves, a foot member carried by said bracket, and means 5 for holding said bearing sleeves and said body together in cooperative relation.

12. In a foot rest, an elongated body, means to 10 secure said body to a fixed support, an upper and a lower bearing sleeve held on said body, the lower sleeve having a thrust bearing part, a bracket having an upper and a lower bearing sleeve to straddle said body and to fit on said first mentioned upper and lower bearing sleeves, a foot member carried by said bracket, means 15 for holding said bearing sleeves and said body together in cooperative relation, one of the first mentioned bearing sleeves having a set of latch-pin receiving recesses spaced apart in a plane transverse of the sleeve, the corresponding second mentioned bearing sleeve having a pin hole, a pin in said pin hole, and a spring continuously 20 tending to advance said pin into one or the other of said recesses.

HENRY JORDAN, JR. 25
